US00D851076S

(12) **United States Design Patent** (10) **Patent No.:** **US D851,076 S**
(45) **Date of Patent:** **** Jun. 11, 2019**

(54) **MOBILE PHONE**

(71) Applicant: **Guangdong Oppo Mobile Telecommunications Corp., Ltd.,**
Dongguan, Guangdong (CN)

(72) Inventor: **Sinan Mu**, Guangdong (CN)

(73) Assignee: **Guangdong Oppo Mobile Telecommunications Corp., Ltd.,**
Dongguan (CN)

(**) Term: **15 Years**

(21) Appl. No.: **29/585,161**

(22) Filed: **Nov. 21, 2016**

(30) **Foreign Application Priority Data**

May 23, 2016 (CN) 2016 3 0196020

(51) LOC (11) Cl. **14-03**

(52) U.S. Cl.

USPC **D14/248**

(58) **Field of Classification Search**

USPC ..... D14/138 AB, 138 AC, 138 C, 138 R,

(57) **CLAIM**

The ornamental design for a mobile phone, as shown and described.

DESCRIPTION

FIG. 1 is a front view of a mobile phone showing my new design;

FIG. 2 is a rear view of the mobile phone of FIG. 1; FIG. 3 is a left side view of the mobile phone of FIG. 1; FIG. 4 is a right side view of the mobile phone of FIG. 1; FIG. 5 is a top view of the mobile phone of FIG. 1; FIG. 6 is a bottom view of the mobile phone of FIG. 1; and, FIG. 7 is a perspective view of the front and right side of the mobile phone of FIG. 1.

The broken lines in the drawings show portions of the mobile phone which form no part of the claimed design.

1 Claim, 6 Drawing Sheets
